UNITED STATES PATENT OFFICE.

JOHN WILLIAM BORE AND HENRY ARTHUR BORE, OF LIVERPOOL, ENGLAND.

ROPE-TEASING MECHANISM.

1,360,875.

Specification of Letters Patent. Patented Nov. 30, 1920.

Application filed July 7, 1919. Serial No. 308,959.

To all whom it may concern:

Be it known that we, JOHN WILLIAM BORE and HENRY ARTHUR BORE, subjects of the King of Great Britain, both residing at 5 Liverpool, in the county of Lancaster and Kingdom of England, respectively, have invented certain new and useful Improvements in Rope-Teasing Mechanism, of which the following is a specification.

10 This invention relates to apparatus for untwisting, breaking up and teasing curled fibers or curled hair or other fibers in the form of ropes and the like for upholstery and other purposes, such apparatus being of 15 the type wherein the rope is passed in the direction of the axis of rotation through a right angled nozzle rotating at considerable speed so as to cause the end to rapidly whirl around in a plane at right angles to the axis 20 of rotation and cause such end to be brought against a teasing device located in the path of the rope paid out from the said nozzle.

The present invention has for its object 25 certain improvements in machines of this kind, these improvements being characterized in that stationary teasing spikes are fixed in the plane of rotation of the rope end so as to project from the inside of the casing within which the nozzle rotates and 30 in that the said casing is so shaped as to form a guide for the end of the rope whirled around by the said nozzle so as to direct it against the spikes, whereby the breaking up and teasing operation is accomplished in a 35 more efficient and expeditious manner than hitherto. These and other improvements will be understood from the following description reference being had to the accompanying drawings in which:—

40 Figure 1 is a side elevation of one spindle machine having a part of the casing removed for the purpose of better illustration,

Fig. 2 is a front elevation,

Fig. 3 is a plan view, and

45 Fig. 4 is an enlarged detail view of the nozzle.

In these figures, 1 are the side frames of the machine, 2 is the driving shaft journaled in bearings in the said side frames and 50 provided with fast and loose pulleys 4, 5 driven from a line of shafting, 6 is a two speed pulley on the end of the shaft 2 for imparting motion by means of belting to a two speed pulley 7 keyed on a countershaft 8. Journaled in bearings on the side frames 55 is a shaft 9 having a pulley 10 or 10^x driven

from a pulley 11 or 11^x on the driving shaft 2, and attached to one end of the shaft 9 is a nozzle 12 turned at right angles at 13 and having a counterweight 14. The inlet 15 of this nozzle is in close proximity to the bracket 16 which is supported on the frame 1, this bracket being made in two halves between which are mounted top and bottom corrugated or spiked feed rolls 17, 18 secured on shafts 19, 20, motion being imparted to the shaft 19 by the worm wheel 21 gearing with the worm 22 on the shaft 8. The shaft 20 is driven by gear wheels 23, 24 from the shaft 19. The shaft 20 is mounted 70 in bearings in the bracket 16 and has a free vertical movement so that the feed rollers 17, 18 may adapt themselves to the varying diameters of ropes to be fed to the machine, the teeth of the wheels 23, 24 being of sufficient length to remain in gear notwithstanding any variation in the distance between the shafts 19, 20 due to the varying diameter of rope fed to the machine. The shaft 20 is pressed downward by weights 25 at the 80 upper ends of rods 26 which are mounted in guides the lower ends of these rods having foot pieces 27 resting on the shaft 20. Thus while the roll 18 can readily accommodate itself to the size of the rope entering 85 between the rolls, such weights will tend to keep the roll 18 pressed downward toward the roll 17. The revolving nozzle 12 is enclosed by a hood or casing 28 so shaped and of such width as to confine and form a guide 90 for the end of the rope whirled around by the end of the nozzle 12. Secured to this hood 28 on the inside and in proximity to the nozzle are a plurality of teasing spikes 95 or teeth 29 to pull apart or tease the rope.

These spikes are driven or screwed through perforations in the hood so as to project on the inside thereof. This teasing device 29 is stationary and has no moving parts, and avoids the necessity of using a rotary teasing cylinder separate from the hood and the guiding of the rope onto these teasing spikes 29 by the hood 28 performs the teasing operation very effectively and in many cases in a superior manner to a revolving teaser. 105 The hood 28 has flanges 30 projecting from it which are respectively bolted at 31 to an arm 32 projecting from the two part bracket 16 and to the bracket 33 secured to the frame 1, these flanges 30 being slotted at 34 for the 110 bolts 31 to pass through, so that by loosening the nuts on the bolts the hood can be

adjusted to move the teasing spikes away from or nearer to the revolving nozzle 12 as may be required according to the quality of rope that is being broken up. The hood 28 is open at the end 36 to permit of the discharge of the material and for part of its length at the sides as shown at 35 to permit of being placed in position and moved over the nozzle 12.

10 The mode of action is as follows:—The machine having been set in motion, the end of a rope to be teased is started between the feed rolls 17, 18. Since the shaft 20 is mounted to move in guides, and pressed 15 downward by the weights 25, the roll 18 accommodates itself to the size of the rope entering between the rolls, and the rope is drawn in between the rolls by the corrugations or spikes carried by the latter. After 20 passing between the rolls, the rope passes into the axial inlet 15 of the angular nozzle 12. This nozzle rotates at high speed with the shaft 9, and its passage being bent at right angles at 13, the rope passes out of 25 the nozzle in a direction radial to the axis of rotation of the nozzle, and is whirled around in a plane approximately normal to the axis of rotation of the nozzle, centrifugal force tending to hold the end of the rope out 30 radially and to draw an increasing length of rope from the nozzle. The nozzle passage may be roughened at 13 and this causes sufficient frictional engagement between the nozzle and the rope to produce an untwisting 35 of the rope between the feed rolls and the portion 13 of the nozzle, the direction of rotation of the nozzle being opposite to the direction of twist of the rope. The rope being thus untwisted and loosened, the 40 shorter fibers fly off by centrifugal force on leaving the nozzle, but the main portion of the rope end whirls around and being guided by the hood is repeatedly struck upon the teasing spikes 29 so that the rope end is disintegrated as fast as fed forward. In this separated or divided state it is discharged from the open end 36 of the hood 28. The process of teasing the rope is thus 45 a continuous one and includes four elements, first the untwisting, second a centrifugal disintegration, third disintegration by impact upon the teasing spikes and fourth a combing action as the end of the rope is drawn across the teasing spikes. It has 50 been found desirable to have considerable range of adjustment of the distance between the rotary nozzle and the teasing spikes to

accommodate different kinds and qualities of rope, and this is provided for by the slots 34.

60

We declare that what we claim is:—

1. In a rope untwisting, breaking up and teasing machine, the combination with a rotary right angled nozzle having a guide passage adapted to receive a rope through its axial arm and discharge it through the radial one, of stationary teasing spikes fixed in the plane of rotation of the rope end, and a hood or casing so shaped as to form a guide for the end of the rope whirled around by the said radial arm so as to direct it against the spikes.

2. In a rope untwisting, breaking up and teasing machine, the combination with a rotary right angled nozzle having a guide passage adapted to receive a rope through its arm and discharge it through the radial one, of a hood to form a guide passage for the end of the rope whirled around by the nozzle, stationary spikes projecting from the inside of the hood and means for adjusting the hood so as to move the teasing spikes away from or nearer to the revolving nozzle.

75

3. In a rope untwisting, breaking up and teasing machine, the combination with a rotary right angled nozzle having a guide passage adapted to receive a rope through its axial arm and discharge it through the radial one and feed rolls adapted to feed the rope in the direction of the axis of the nozzle, of weights secured at the upper ends of rods mounted in suitable guides and foot pieces at the lower ends of such rods adapted to rest upon the shaft of the upper roll for keeping the upper roll pressed downward toward the lower one.

80

4. In a rope untwisting, breaking up and teasing machine as claimed in claim 3, mounting the feed rolls in brackets divided perpendicularly into two halves in which the weight rods are respectively mounted in guides and forming the hood with flanges projecting from it which are respectively bolted to an arm projecting from the said bracket and to an arm secured to the frame.
